UNITED STATES PATENT OFFICE.

KATHLEEN M. POLHAMUS, OF SOUTH PASADENA, CALIFORNIA.

DESIGN FOR A HAT.

56,991.

Specification for Design.

Patented Jan. 25, 1921.

Application filed March 30, 1920. Serial No. 370,013. Term of patent 7 years.

To all whom it may concern:

Be it known that I, KATHLEEN M. POLHAMUS, a citizen of the United States, residing at South Pasadena, in the county of Los Angeles and State of California, have invented a new, original, and ornamental Design for Hats, of which the following is a specification, reference being had to the accompanying drawing, forming a part thereof.

Fig. 2 is a rear view in perspective.

Fig. 3 is a side view in perspective of a hat as shown.

I claim:

The ornamental design for a hat as shown.

KATHLEEN M. POLHAMUS.
